[57] CLAIM

The ornamental design for a container opening tool, substantially as shown and described.

DESCRIPTION

FIG. 1 is a perspective view of the invention.
FIG. 2 is a side elevational view of FIG. 1, the opposed side is a mirror image thereof.
FIG. 3 is a bottom plan view of FIG. 1.
FIG. 4 is a top plan view of FIG. 1.
FIG. 5 is a left end elevational view of FIG. 1; and,
FIG. 6 is a right end elevational view of FIG. 1.
